CLAIM

The ornamental design for a bib garment, as shown and described.

DESCRIPTION

FIG. 1 is an environmental perspective view of a bib garment design in use on a person;

FIG. 2 is a perspective view of the bib garment design;

FIG. 3 is a front view thereof;

FIG. 4 is a back view thereof;

FIG. 5 is a top view thereof;

FIG. 6 is a bottom view thereof;

FIG. 7 is a right side view thereof;

FIG. 8 is a left side view thereof;

FIG. 9 is a cross sectional top plan view taken along line 9-9 in FIG. 4, showing the waist pocket detail of the claimed design;

FIG. 10 is a cross sectional top plan view taken along line 10-10 in FIG. 4, showing the wrist pocket detail of the claimed design;

FIG. 11 is an environmental perspective view of an alternative embodiment of the bib garment design, unfolded and in use on a person;

FIG. 12 is a perspective view of the alternative embodiment of the bib garment design;

FIG. 13 is a front view of the alternative embodiment of the design.

FIG. 14 is a back view of the alternative embodiment of the design.

FIG. 15 is a top view of the alternative embodiment of the design.

FIG. 16 is a bottom view of the alternative embodiment of the design.

FIG. 17 is a right side view of the alternative embodiment of the design.

FIG. 18 is a left side view of the alternative embodiment of the design.

(Continued)

FIG. 19 is a cross sectional top plan view taken along line 19-19 in FIG. 14, showing the waist pocket detail of the alternative embodiment of the claimed design; and, FIG. 20 is a cross sectional top plan view taken along line 20-20 in FIG. 14, showing the wrist pocket detail of the alternative embodiment of the claimed design.

The broken lines shown in the drawings represent environment associated with the claimed design and form no part thereof.
